TROLLEY BASE

Charles I. Earll, York, Pa.

Application August 12, 1935, Serial No. 35,794

4 Claims. (Cl. 191—68)

My invention relates to trolley bases and particularly to trolley bases used in connection with trackless trolleys, where two trolley poles are used and these poles have a wide lateral swing. 5 When the trolley leaves the wire at a time when the pole is a considerable distance out at the side, and a retriever pulls it down the side pull of the trolley rope swings the pole violently towards the center of the car. The pole will start 10 towards the center of the car immediately upon leaving the wire and this will retard the action of the retriever, and when the retriever is thrown into action the pole is swung violently towards the center of the car and frequently strikes the 15 rope of the other pole, causing it to leave its wire, making it necessary for the operator to restore both poles to the wire.

The object of my invention is to provide a means for automatically and effectively retarding the side swing of the pole as soon as it leaves the wire. In the drawing accompanying and forming part of this specification, Fig. 1 is a plan view, with certain parts omitted, of the preferred form of my invention. Fig. 2 is a 20 side elevation and Fig. 3 is a section on line 25 3—3 of Fig. 1. The reference numerals are used in the same sense in the drawing and specification.

Numeral 1 is a support adapted to be bolted 30 to the roof of the vehicle. It is provided with the central pin 2, on which is pivotally mounted the turret 3, and it is provided with horizontal pivots 4 for the trolley pole holding means, the pivots 5 for the springs 6 which press the pole 35 upward in the usual manner. The support is provided with a cylindrical recess 7 and the turret 3 is provided with a flange 8, which covers said recess. Said flange has pivots 9, on which are mounted the brake members 10. Secured to the 40 under side of the flange 8 is the hydraulic cylinder 11 having pistons therein connected with brake members or shoes 10. The cylinder 11 is connected by a flexible tube 12 with the cylinder 13. The cylinder 13 is secured to the lower side 45 of the pole-holding member 14, and the piston in said cylinder 13 is connected by the rod 15 with the bell crank 16. The cylinder 13 is connected by the pipe 17 with the supply chamber 18. The bell crank 16 has a yoke 19 connected 50 to it and said yoke is adapted to be secured to the trolley rope. A spring 20, having one end secured to the bracket 21 and the other end to the piston 22 in the cylinder 13, tends to withdraw the piston 22 from the cylinder 13. The 55 spring 20 has strength sufficient to overcome the

normal pull of the trolley rope when the trolley is on the wire. This pull is only that given by the weak spring in the retriever which takes in the slack rope, generally from four to six pounds as is well understood in the art. When the trolley 5 first leaves the wire, the rope which is connected with the retriever will be given a strong pull, approximately equal to the normal pressure of the trolley against the wire, about thirty pounds. This pull will be sufficient to overcome 10 the spring 20 and apply pressure to the brake shoes 10, and press them out against the cylindrical rim 23.

In a fraction of a second after the trolley leaves the wire and starts upward the strong retrieving 15 spring of the retriever will be put into operation, and this will put a pull of from sixty to eighty pounds on the rope, and produce a much greater braking action by the shoes 10. As the pole descends this braking action will decrease and permit the pole to swing gently back to its central 20 position.

Having thus described my invention what I claim is:—

1. In a trolley base the combination with a support adapted to be secured to the roof of a vehicle, of a turret pivotally mounted on said support, a trolley pole, a pivoted connection for the trolley pole on said turret, a trolley rope, means on said pole connected with the trolley rope and means operated by a pull on the trolley rope above a predetermined limit to retard the turning of said turret towards its central position when said pole has left its wire at the side of its central position. 25

2. In a trolley base the combination with a support, a brake drum formed thereon, a turret pivotally mounted on said support, brake shoes adapted to engage said drum mounted on said turret, an hydraulic cylinder, pistons therein adapted to operate said brake shoes, a trolley pole holding member pivotally connected with said turret, a pressure cylinder mounted on said pole holding member, and a flexible tubular connection between said pressure cylinder and said hydraulic cylinder secured to said turret. 30

3. In a trolley base a combination with a support and a rotatable turret on said support, of a pole pivotally connected with said turret for vertical movement, friction clutch members operatively mounted on said turret adapted to engage a friction drum formed on said base, a clutch operating lever pivotally mounted on said pole near its free end adapted to be secured to the upper end of trolley rope, connections between 40 45 50 55

said lever and said clutch members whereby a pull on the rope above a predetermined limit operates said clutch member.

4. In a trolley base a combination with a support adapted to be secured to the roof of a vehicle, of a turret rotatably mounted on said support, a trolley pole, a pivotal connection for the trolley pole on said turret, a trolley rope con-

necting means on said pole, means operated by a pull above a predetermined limit on the trolley rope to retard the turning of said turret including means whereby said turret is free to turn when the pull on the rope is below a predetermined limit.

CHARLES I. EARLL.
